UNITED STATES PATENT OFFICE.

LEMUEL W. SERRELL, OF PLAINFIELD, NEW JERSEY.

FIRE-EXTINGUISHER.

1,150,634.

Specification of Letters Patent. Patented Aug. 17, 1915.

Application filed February 7, 1914. Serial No. 817,111.

To all whom it may concern:

Be it known that I, LEMUEL W. SERRELL, a citizen of the United States, and a resident of Plainfield, in the county of Union and State of New Jersey, have invented certain new and useful Improvements in Fire-Extinguishers, of which the following is a specification.

The object of this invention is to provide a fire extinguisher which is simple in construction, susceptible of manufacture at low cost, reliable and efficient, easy to re-charge, and which requires but a single movement for its operation.

A practical embodiment of the invention is illustrated in the accompanying drawing and will now be briefly described, it being understood that, while the details of construction herein shown are deemed preferable and in fact constitute important specific features of novelty, numerous changes may be made without departing from the substance of the invention.

In the said drawings, Figure 1 is a vertical section through the fire extinguisher, parts being broken away and parts shown in elevation; Fig. 2 is a sectional plan on the line 2—2 of Fig. 1; and Fig. 3 is a bottom plan view.

An elongated hermetically-closed metal container 10 affords in its interior a chamber 11 for the reception of a suitable liquid, indicated at 12, and air or other gas under pressure for the purpose of driving out the liquid when the outlet is opened.

At one end of the container, which may be regarded as the upper end, is a reduced portion or neck 13, affording in its interior an outlet or valve chamber 14. This chamber is separated from the main chamber by a wall constituted by an apertured plug 15, which is screwed into the base of the neck. An outlet nozzle 16 extends laterally from the neck, its discharge passage being in communication with the outlet chamber.

An outlet pipe 17 is disposed within the container, being secured in and entirely filling the aperture in the plug 15, so that the pipe constitutes the means of communication between the main chamber and the outlet chamber. Its inlet end is adjacent the bottom of the container, and the compressed air being above the level of the liquid, only the liquid is driven forth when the way is opened and as long as any liquid remains.

In order to insure the complete emptying of the liquid, irrespective of the angle at which the container is held, the latter is provided in its bottom with a well 18, into which the inlet end of pipe 17 projects and toward which the bottom slopes from all directions, as shown. This well is formed by a cupped cap 19, which constitutes a closure for an opening in the lowest part of the bottom. The said cap is preferably screwed in place and afterward soldered to prevent leakage. It serves the dual function of enabling the container to be re-charged with liquid and of affording access to the inlet end of the pipe 17, for the purpose of renewing the seal 20 hereinafter described. The end of the pipe extends beyond or below the opening, so that when the cap 19 is removed it is in projecting relation, and consequently conveniently disposed for the said renewal of the seal. The cap 19 is also provided with an opening, which is normally closed by a taper, driven plug 21. This small opening is for the purpose of re-charging the container with compressed air after the admission of the liquid; and the driven plug affords a simple and reliable means for closing the opening and holding the pressure.

The outlet chamber 14 is provided below the outlet 16 with an annular valve seat 22, with which co-operates a bodily movable valve 23, the latter being formed with an upward-projecting stem 24, which is engaged and actuated by a rotary operating member 25. Said member is preferably arranged so as to be rotatable about a longitudinal axis, that is to say, an axis parallel to the movement of the valve; and suitable means are provided whereby this rotary movement of the operating member produces longitudinal movement of the valve. For this purpose the valve stem is preferably externally screw-threaded, and the operating member has an internally-threaded barrel 26 engaging the same. The reduced portion or shaft 27 of the operating member passes through an opening in an apertured flange 28 at the top of the neck and is provided at its upper end with an operating handle or wheel 29. A tight joint is insured by a packing or washer 30 inserted between the flange 28 and the barrel 26, the opposing surfaces of the flange and barrel being formed with opposing annular ridges 31, which press into the packing, as indicated.

- A spring 32 interposed between the flange 28 and the disk 29 holds the joint in compression and is preferably housed within a skirt 33 depending from the handle and inclosing the upper end of the neck. When the extinguisher is in use, the fluid pressure against the under side of the valve forces the operating member against the washer, and thus aids in keeping the joint tight.
- 10 Apertured lugs 34 may be provided on the said skirt and neck, respectively, for the reception of the light wire of a lead seal, which is readily broken by the turning of the handle.
- 15 The valve stem 24 is made hollow for the reception of the upper end of the pipe 17, which thus extends above the valve seat and co-acting valve portion. The pipe also constitutes a guide for the valve, preventing 20 turning of the latter, and to this end is preferably made square as shown, the recess in the valve stem being similarly formed, but sufficiently larger to permit the liquid to pass downward from the upper end of the 25 pipe beneath the valve and thus through the discharge opening when the valve is unseated.

The rupturable seal 20 hereinbefore referred to consists of a thin metal wafer or 30 diaphragm soldered or otherwise suitably applied to the inlet end of the pipe 17, in such manner as to prevent access of the liquid to the outlet valve until such time as the extinguisher is to be used, when the 35 same movement which is required to open this valve also ruptures or punctures the diaphragm. To this end a puncturing device or rod 35 is disposed within the pipe 17, leaving adequate passageway for the 40 liquid, as shown, the lower end of this rod being pointed and engaged with or immediately above the seal 20, while its opposite end projects above the upper end of the pipe so as to be thrust downward by the closed 45 top of the hollow valve stem when the latter is moved downward in the unseating movement of the valve. It will be observed that the seal is in effect interposed between the outlet valve and the interior of the container.

It will be apparent that until used the pressure container is hermetically closed, so 50 that leakage and loss of pressure are impossible. The one operation of the operating member ruptures the seal interposed between the contents of the container and the discharge nozzle, and also opens the outlet valve. A like movement in the opposite direction serves to close the valve. The valve 55 is not called upon to hold the pressure during such period as the extinguisher may be kept ready for use, but enables the discharge to be stopped and started after the rupture of the seal, thus enabling the user to distribute 60 the discharge over such period and in as

many separate discharges as may seem desirable. Whenever the valve is closed, after the rupture of the seal, it is liquid which is maintained in contact with the co-operative portions of the valve seat and valve, and not air or gas, thus assisting the valve in holding the pressure when closed. The container is readily re-charged with liquid by removing the filling cap at the bottom, and the same closure affords access to the inlet 70 end of the pipe 17, so that the seal 20 may be renewed. The air pressure is re-introduced in the manner already indicated.

What I claim as new is:

1. A fire extinguisher comprising a hermetically sealed container charged with liquid and compressed air tending to drive the liquid out, an outlet from said container, a valve closing said outlet and adapted to hold the pressure in the container, operating 80 means for opening and closing the valve at will, an outlet pipe extending to near the bottom of the container, a seal at the lower end of said pipe between the valve and the liquid in the container, and an element operatively related to the valve-operating means whereby the one is operated by the other to destroy said seal when the valve is opened.

2. In a fire extinguisher, the combination 95 of a container having an outlet tube leading from near its bottom and terminating in an outlet, a valve therefor, a handle for operating the valve, a seal for said pipe, and a puncturing rod extending through said tube 100 and correlated with said handle and valve to be actuated thereby.

3. A fire extinguisher, comprising a hermetically sealed container charged with liquid under pressure tending to drive it out 105 and having a conical bottom, in combination with an outlet tube extending substantially to the lowest part of said bottom, an outlet valve adapted to hold the pressure in the container, means for opening and closing the valve at will, a seal normally closing the outlet tube and interposed between the valve and the liquid in the container, and means for rupturing said seal by the same operation required to open said valve.

4. In a fire extinguisher, the combination of a container having a well in its bottom and said bottom sloping from all directions to said well, an outlet tube having its lower end extending into said well, a seal for the tube, 110 an outlet valve, a seal-rupturing member, and common means for operating said valve and seal-rupturing member.

5. A fire extinguisher, comprising a container having a well with a removable piece, 115 an outlet pipe having its inlet end extending into said well and there provided with a seal, and a seal-rupturing member.

6. In a fire extinguisher, the combination of a pressure container, an outlet pipe ex- 130

5 tending to near the bottom thereof, a seal for the lower end of said pipe, seal-destroying means, and means at the lower end of the container for giving access to the end of the pipe for renewing the seal.

7. A fire extinguisher, comprising a pressure container having an opening, an outlet pipe having its inlet end projecting through and beyond said opening and provided with 10 a seal, a cap closing said opening and inclosing the sealed end of said pipe, a handle, and a member operated by the handle for destroying said seal.

8. A fire extinguisher, comprising a pressure container, an outlet pipe therein, a seal applied to the inlet end of said pipe, and operating means for destroying said seal, in combination with a removable piece adjacent the inlet end of said pipe for giving 20 access thereto, said removable piece having means therein for admitting air or gas under pressure.

9. A fire extinguisher, comprising a pressure container having an outlet, a valve therefor movable lengthwise of the container, a rotary handle for operating the valve, a puncturing member connected to said valve, an outlet pipe in said container surrounding said member, and a seal applied 30 to the lower end of said pipe.

10. A fire extinguisher, comprising a hermetically sealed container charged with liquid under pressure tending to drive it out, said container embodying an outlet and a 35 valve adapted to hold the pressure in the container, a discharge pipe leading to the outlet from near the bottom of the container, a seal interposed between the valve and the interior of the container and normally keeping the liquid from the valve, and seal rupturing means connected with the valve.

11. In a fire extinguisher, the combination of a container for holding liquid and air under pressure to drive the liquid out, a discharge tube in the container having a rupturable seal at its inlet end, a rupturing device, a cap for giving access to said inlet end and having an air charging orifice, and a plug for said orifice.

12. A fire extinguisher comprising a container having a chamber for holding liquid and air under pressure, an outlet valve chamber having a valve seat, a valve in said valve chamber, and an operating member for moving said valve away from its seat, in combination with an outlet pipe within the first-named chamber, said pipe extending into said valve chamber beyond said valve seat.

13. In a fire extinguisher, the combination 10 of a chamber for holding liquid and air under pressure, an outlet chamber, a valve controlling the discharge from said chamber, and means affording an outlet passage having its inlet end near the bottom of the first-named chamber and delivering into said out-

let chamber above said valve, said chambers being otherwise cut off from communication with each other.

14. A fire extinguisher comprising a container having a chamber for holding liquid and air under pressure, an outlet chamber having a valve seat, a hollow valve movable to and from said seat, and means for conducting the liquid from near the bottom of the first-named chamber into said outlet 75 chamber comprising a tube extending within said hollow valve.

15. A fire extinguisher comprising a container having a chamber for holding liquid and air under pressure, an outlet chamber having a valve seat, a valve coöperating with said seat and having a hollow stem extending upward above the same, an operating device coöperating with said valve to depress the same, and an outlet tube leading 80 from near the bottom of the first-named chamber and extending upward into said hollow stem.

16. The combination of a container having a chamber for holding liquid under gas pressure, an outlet chamber separated from the other chamber by a wall, said outlet chamber having a valve seat, a valve in said outlet chamber movable toward and from said seat, an operating member rotatable 90 about an axis parallel to the direction of movement of said valve, and an outlet tube secured in an opening in said wall and entering said valve, being formed to prevent the latter from turning.

17. In a fire extinguisher, the combination of a container having a chamber for holding liquid under gas pressure, an outlet chamber, a hollow outlet valve therein, an outlet pipe forming the communication between 105 said chambers, said pipe having its upper end received within said hollow valve and a seal for its lower end, and a puncturing rod passing through said pipe and having its upper end bearing against the inside of the 110 top of said valve to be actuated thereby.

18. In a fire extinguisher, the combination of a container for holding liquid under gas pressure, an outlet valve adapted to hold the pressure in the container, an operating member for opening and closing the same at will, an outlet pipe for conducting liquid from near the bottom of said container to said valve, a seal for the inlet end of said pipe interposed between the valve and the 120 interior of the container, and a seal-rupturing member arranged to be engaged and actuated by said valve.

19. In a fire extinguisher, the combination of a container having a neck formed at the 125 top with an apertured flange, an outlet valve having a hollow stem extending upward in said neck, an operating barrel rotatable in said neck and receiving and engaging said stem, an operating shaft extending upward 130

from said barrel through said apertured flange, a wall between said neck and the main interior of the container, and an outlet pipe passing through said wall into said 5 hollow stem.

20. The combination of a container for holding liquid under gas pressure, a neck on the container having an apertured top flange, a wall separating the interior of the 10 neck from the interior of said container, an outlet pipe secured in an opening in said wall, an outlet valve above said wall, an operating barrel rotatable in said neck and having a reduced portion extending through 15 said apertured flange, the opposed portions of said flange and barrel having annular ridges, a packing therebetween, and a spring arranged to press said barrel against the packing.
- 20 21. In a fire extinguisher, the combination of a container for holding liquid under gas pressure, an outlet chamber, a valve control-

ling the discharge therefrom, an apertured plug separating said chamber from the interior of the container, and an outlet pipe 25 secured in the aperture of said plug for conducting the liquid from the interior of said container into said outlet chamber.

22. In a fire extinguisher, the combination of a container for holding liquid under gas 30 pressure, a neck on the container having an apertured top flange, an outlet valve, a rotary operating device in said neck having a reduced portion passing through said apertured flange, a skirt on said reduced portion, 35 and a spring housed in said skirt and bearing against the top of said flange.

In witness whereof I have signed my name in the presence of two subscribing witnesses.

LEMUEL W. SERRELL.
